US0D1072614S

(12) **United States Design Patent** (10) **Patent No.:** **US D1,072,614 S**
(45) **Date of Patent:** **** Apr. 29, 2025**

(54) **BOTTLE**

(71) Applicant: **Zestron Corporation**, Manassas, VA (US)

(72) Inventor: **Michael Alexis Ladinig**, San Marcos, CA (US)

(73) Assignee: **Zestron Corporation**, Manassas, VA (US)

(**) Term: **15 Years**

(21) Appl. No.: **29/965,590**

(22) Filed: **Sep. 27, 2024**

(51) LOC (15) Cl. **09-01**

(52) U.S. Cl.

USPC **D9/537**

(58) **Field of Classification Search**

USPC D9/537, 549, 545, 688, 690

CPC B65D 1/0223

See application file for complete search history.

(57) **CLAIM**

The ornamental design for a bottle, as shown and described.

DESCRIPTION

FIG. 1 is a top perspective view of a design for a bottle;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top perspective view thereof shown engaged with an unclaimed spray bottle topper.

The broken lines in FIG. 8 showing a spray nozzle top illustrate environmental structure and form no part of the claimed design. The remaining broken lined portions of the bottle form no part of the claimed design.

1 Claim, 7 Drawing Sheets
